CLAIM

The ornamental design for a packaging, as shown and described.

DESCRIPTION

FIG. 1 is a perspective view of a packaging showing my new design.

FIG. 2 is a left view thereof.

FIG. 3 is a right view thereof.

FIG. 4 is a front view thereof.

FIG. 5 is a rear view thereof.

FIG. 6 is a top view thereof.

FIG. 7 is a bottom view thereof.

FIG. 8 is a perspective view thereof, shown without the top for clarity of illustration.

FIG. 9 is a left view thereof, shown without the top for clarity of illustration.

FIG. 10 is a right view thereof, shown without the top for clarity of illustration.

FIG. 11 is a front view thereof, shown without the top for clarity of illustration.

FIG. 12 is a rear view thereof, shown without the top for clarity of illustration.

FIG. 13 is a top view thereof, shown without the top for clarity of illustration.

FIG. 14 is a bottom view thereof, shown without the top for clarity of illustration.

FIG. 15 is an exploded perspective view of the packaging showing my new design.

FIG. 16 is a cross-sectional view thereof, bisecting the packaging as reflected in FIG. 6; and,

FIG. 17 is a cross-sectional view thereof, shown without the top merely for clarity of illustration, bisecting the packaging as reflected in FIG. 13.

The short-dash short-dash broken lines illustrate portions of the packaging. The long-dash short-dash broken lines represent boundary lines and define the bounds of the claim. The broken lines form no part of the claimed design. The space between the short-dash short-dash lines and the boundary lines also forms no part of the claimed design. The shade lines shown represent surface shading and not surface ornamentation, color, or material type.
